ATTORNEY

UNITED STATES PATENT OFFICE.

BENJAMIN F. BLAKEMAN, OF GREENSBORO, NORTH CAROLINA, ASSIGNOR OF ONE-HALF TO ALVIS W. CRAVER, OF GREENSBORO, NORTH CAROLINA.

COPYHOLDER.

Application filed July 18, 1925. Serial No. 44,529.

To all whom it may concern:

Be it known that I, BENJAMIN F. BLAKEMAN, a citizen of the United States, residing at Greensboro, in the county of Guilford and 5 State of North Carolina, have invented a new and useful Copyholder, of which the following is a specification.

This invention relates to a copyholder for use by stenographers, typists and the like.

10 The invention has for its objects to provide a copyholder which will be simple in its construction and operation and comparatively inexpensive; which will feed copy of any length or width, either thick or 15 thin, such as copy tissue or cardboards in which variable spacing may be effected without any adjustment, and in which copy may be inserted or removed with a minimum amount of time and trouble.

20 The detailed construction of the invention together with its objects and advantages will be more fully explained in connection with the accompanying drawings which illustrate the preferred form of the invention.

25 In the drawings—

Fig. 1 is a perspective view of the invention;

Fig. 2 is a vertical section thereof taken on the line 2—2 of Fig. 1;

30 Fig. 3 is a vertical section through the housing at the base of the holder;

Fig. 4 is a detailed sectional view taken transversely of the rear portion of the housing;

35 Fig. 5 is a section taken longitudinally of the roller or platen;

Fig. 6 is a detail sectional view taken through the thumb wheel by means of which the copy is advanced;

40 Fig. 7 is a section through the upper part of the copyholder, showing the card holder attachment;

Fig. 8 is a perspective view of the upper 45 part of the copyholder with the card holder attachment thereon.

Referring in detail to the drawings, the invention comprises a U-shaped frame 10, having an upper horizontal leg 11 and a lower horizontal leg 12, the end of the latter being secured in a metal block 13 at the rear end of a housing 14. Rubber cushions or sleeves 15 surround the leg 12, and are adapted to rest on a desk or table. It is preferred to secure the end of the leg 12 in the block 13 by means of a set screw 16, or the

like, so that the frame 10 may be adjusted at any desired angle.

The upper leg 11 of the U-shaped frame is formed with a return bend 17 on which a roller or platen 18 is rotatably mounted. 60 A spring metal plate 19 is secured at its lower end to the leg 12, and at its upper end is provided with a forwardly projecting screw-threaded pin 20, on which is mounted a line guide 21, adapted to bear against the roller 18. The line guide is frictionally held in position by a thumb screw 22, which also serves to hold a finger 23, which normally projects upwardly above the roller and prevents the copy from bending forwardly as 65 it is advanced upwardly over the roller.

The roller 18 is covered with soft rubber, and the friction between the same and the paper is so much greater than the friction between the paper and the line guide 21, that there is no slippage between the copy and the roller. The roller has heads 24 and 25 secured in its ends which are rotatably mounted on the return portion 17 of the upper leg of the frame, and the head 25 is formed with a pulley 26, which is adapted to be actuated by means of a suitable belt 27, or the like, to rotate the roller.

The belt 27 passes from the pulley 26 downwardly through a recess 28 formed at the rear end of the housing 14 and beneath idler pulleys 29 which are rotatably mounted on a spacer sleeve 30 secured between the sides of the housing. From the pulley 29 the belt 27 extends to the forward end of the housing 14 and about a thumb wheel or pulley 31, which is rotatably mounted on a spacing sleeve 32 secured between the sides of the housing at the front end. The housing is cut away as at 33 sufficiently so that the thumb or finger may engage the pulley 31 to rotate the same. Slots 34 are cut in the front end of the housing to provide fingers 35 about which may be secured a rubber cushion 36 for supporting the front end of the housing. A spacer 37 may be secured between fingers 35 to prevent the latter from being bent inwardly.

The copyholder is supported mainly by the rubber sleeves 15, and it is braced by the housing 14, which also serves to prevent anything from getting caught in the belt 27. The copyholder is so shaped that the U-shaped frame 10 may rest on a desk behind the typewriter, while the housing 14 extends 105 110

forwardly at the side of the typewriter, and the thumb wheel or pulley 31 is within easy reach. The copy may be placed on the roller 18 by simply bending the spring plate 19 forwardly by means of the thumb screw or knob 22. The spring plate may be pulled forwardly to permit the copy to be straightened or the line guide, which is frictionally held may be turned about the pin 20 as an axis to follow the line.

When the first line has been copied, the operator pushes the upper edge of the thumb wheel forwardly until the next line is in position. The extent of movement of the copy is governed by the amount of movement of the thumb wheel; a short push moves the copy a small distance, and a longer push moves the copy a correspondingly greater distance. The copy may be moved backwardly by pulling on the thumb wheel instead of pushing. The thumb engages the belt as well as the thumb wheel, so that slippage of the belt on the wheel is prevented.

While the roller 18 will feed cards in the same manner as other copy, it is preferred to provide an attachment whereby a pile of cards may be supported and removed one at a time as they are copied. This attachment, as shown in Figures 7 and 8, consists of a backing plate 38, having a strip 39 secured to its rear face near the lower edge thereof, and adapted to rest on the upper surface of the roller with its rear portion extending beneath the leg 11. The front portion of this strip 39 extends forwardly beneath the lower edge of the plate 38 to form a shelf 41 on which the lower edge of the card may rest. When this attachment is used, the roller 18 remains stationary, and the finger 23 may be turned to one side out of the way of the attachment, as shown in Figure 8.

While I have shown and described in detail the preferred form of the invention, it is obvious that various modifications may be made therein without any material departure from the essential features of the invention. It is my purpose to include all such modifications within the scope of the appended claims.

What I claim is—

1. In a copyholder, the combination of a U-shaped frame having substantially parallel legs arranged one above the other, a roller rotatably mounted on the upper leg and having a frictional surface, a spring plate secured to and extending upwardly from the lower leg and bearing against the roller to hold the copy, a line guide carried at the upper end of the plate, and means for rotating the roller in either direction to move the copy up or down.

2. In a copyholder, the combination of a U-shaped frame having substantially parallel legs arranged one above the other, a roll-

er rotatably mounted on the upper leg and having a frictional surface, a spring plate secured to the lower leg and bearing against the roller, a line guide carried by said plate adjacent the roller, said line guide being centrally pivoted for adjustment with respect to the plate in a plane tangent to the roller, means for frictionally holding the said line guide in its adjusted position, and means for rotating the roller in either direction to move the copy up or down.

3. In a copyholder, the combination of a frame adapted to rest on a desk and having substantially parallel upper and lower members, a roller rotatably mounted on the upper member and having a frictional surface, a spring plate secured to and extending upwardly from the lower member and bearing against the roller to hold the copy theron, a line guide at the upper end of the spring plate, said line guide being centrally pivoted and frictionally held to the plate so that it may be adjusted to align it with the lines of the copy with the latter in any position, and means for rotating the roller in either direction to move the copy up or down.

4. In a copyholder, the combination of a frame adapted to rest on a desk and having substantially parallel upper and lower members, a roller rotatably mounted on the upper member and having a frictional surface, a spring plate bearing against the roller to hold the copy, a housing secured to and extending forwardly from the lower part of said frame and constituting a brace for supporting the frame in upright position, and means extending longitudinally within the housing and connected to the roller for rotating the latter to move the copy up or down.

5. In a copyholder, the combination of a frame having substantially parallel upper and lower members, a roller rotatably mounted on the upper member and having a frictional surface, a spring plate bearing against the roller to hold the copy, a housing secured to and extending forwardly from the lower part of said frame and constituting a brace for supporting the frame in upright position, a thumb wheel mounted in the front part of the housing, pulleys at the rear end of the housing, a pulley secured to the end of the roller above the rear end of the housing, and a belt connecting said pulleys and thumb wheel whereby the latter may be rotated to rotate the roller and move the copy up or down.

6. In a copyholder, the combination of a U-shaped frame having substantially parallel legs arranged one above the other, a roller rotatably mounted on the upper leg and having a frictional surface, a spring plate bearing against the roller to hold the copy, a housing extending forwardly from the end of the lower leg of the frame and

constituting a brace for supporting said frame in upright position, said lower leg being adjustably connected with the housing so that the U-shaped frame is angularly adjustable forwardly or backwardly, and means extending longitudinally within the housing and connected to the roller for ro-

tating the latter to move the copy up or down.

In testimony that I claim the foregoing ¹⁰ as my own, I have hereto affixed my signature.

BENJAMIN F. BLAKEMAN.
